MAGNETIC TAPE SOUND RECORDING AND REPRODUCING MACHINE

Gerhard Dietrich, Furth, Bavaria, Germany, assignor to
Max Grundig Furth, Germany

Filed Oct. 15, 1965, Ser. No. 37,494

Claims priority, application Germany May 28, 1965

Term of patent 14 years

(Cl. D26—14)

FIG.1

FIG.2

FIG.3

FIG.4

FIG.5

FIGURE 1 is a front, top and right side perspective view of a magnetic tape sound recording and reproducing machine, showing my new design;

FIGURE 2 is a front view in elevation;

FIGURE 3 is a left side elevational view, the right side being substantially a mirror image thereof;

FIGURE 4 is a top plan view; and

FIGURE 5 is a back side view in elevation.

I claim:

The ornamental design for a magnetic tape sound recording and reproducing machine, as shown and described.
